UNITED STATES PATENT OFFICE.

SEDWICK MILLS WADE AND GEORGE EDWARD GARNER, OF ANDOVER,
OHIO.

ROTARY ENGINE.

SPECIFICATION forming part of Letters Patent No. 759,779, dated May 10, 1904.

Application filed September 2, 1903. Serial No. 171,652. (No model.)

To all whom it may concern:

Be it known that we, SEDGWICK MILLS WADE and GEORGE EDWARD GARNER, citizens of the United States, and residents of Andover, in the 5 county of Ashtabula and State of Ohio, have invented new and useful Improvements in Rotary Engines, of which the following is a full, clear, and exact description.

This invention relates to improvements in 10 steam-engines, and particularly appertains to certain novel and useful improvements in rotary engines.

In carrying out the present invention we have in contemplation the provision of a mechanism of the class described which will be 15 simple in its construction, positive in its operation, and embodying the desired features of durability and economy.

A further object of the invention is to provide 20 a rotary engine, the internal revoluble disk of which is supplied with a plurality of spring-tensioned pistons designed to be operated by the pressure of steam within the casing of the engine for the purpose of turning 25 a power-shaft.

Still another object of the invention is to provide 30 a number of revolving abutments having grooves or recesses therein, said abutments being operated through the medium of the revolution of the disk of the engine in such manner that the recesses will be brought into a predetermined position at certain times to permit the passing of the pistons.

With the above-recited objects and others 35 of a similar nature in view our invention consists in the construction, combination, and arrangement of parts, as is described in this specification, delineated in the accompanying drawings, and set forth in the appended claims.

Reference is to be had to the accompanying 40 drawings, forming a part of this specification, in which similar characters of reference indicate corresponding parts in all the figures.

Figure 1 is a view in side elevation of an 45 engine embodying our improvements. Fig. 2 is a similar view with one of the sections of the casing removed to show the interior construction of the mechanism. Fig. 3 is a view in side elevation of our improved engine, the

valve-housing being removed and a portion 50 of the casing broken away to show the relative position occupied by the pistons and the revolving abutments at certain times. Fig. 4 is a cross-sectional view taken through the engine substantially on the line 4-4 of Fig. 3, 55 such view illustrating the passage of the steam into the engine. Fig. 5 is a view taken on the line 5-5 of Fig. 3. Fig. 6 is a vertical sectional view taken through the engine on the line 6-6 of Fig. 1. Fig. 7 is a detail view 60 of the valve for controlling the admission of steam through the engine, and Fig. 8 shows a modified form of abutment-disk.

Referring now to the accompanying drawings in detail, 5 indicates the base of the casing of our improved engine, said casing being formed of two sections 6 and 7, which sections are connected through the medium of a plurality of bolts 8 passing through alining apertures formed in the flanged end portions of 70 the casing. Extending centrally through the casing is a main shaft 9, carrying a belt-pulley 10, and mounted upon said shaft within the casing is the disk 11 of the engine, said disk being of less diameter than the interior of the 75 casing, so that an annular chamber 12 is formed between the inner circular wall of the casing and the outer surface of the disk wheel.

Mounted circumferentially of the disk are a number of pistons 13, each piston comprising 80 a supporting-block 14, having a groove or recess 15 therein, within which recess is seated a spring 16, carrying at its outer end a block 17. We have also arranged circumferentially of the disk wheel a number of packings 18, each 85 packing being pressed outward through the medium of a spring 19, these spring-pressed packings being placed so as to lie at the point of contact of the abutment-blocks and the piston.

It will be seen by reference to the drawings that the casing near the base is provided with small supplemental chambers 20, said chambers being arranged on opposite sides of the main chamber, and passing through each of 90 said chambers is a shaft 21, there being mounted upon the shaft within the chamber an abutment block or disk 22, these disks being formed

of any solid material and are each formed with a cut-away portion 23, such cut-away portion being designed when the shafts 21 21 are rotated, as hereinafter described, to be presented 5 toward the opening or main chamber, so that the pistons may readily pass said abutments. The chambers may be of any suitable character, care being taken, however, to have them of such form that a space is left back of the 10 abutment-blocks, whereby friction is avoided on the surface of the said blocks opposite the point of pressure. The shafts 21 21 extend transversely entirely through the casing, and mounted upon each shaft at the exterior of 15 the casing is a toothed gear-wheel 24, these gear-wheels being designed in turn to mesh with and be driven by a relatively large gear-wheel 25, mounted upon the main shaft 9 at the exterior of the casing.

20 In order to operate or drive the engine, the steam is admitted through the steam-pipe 26 into a channel or cavity 27, formed in the valve housing or casing 28, which housing is secured to one side of the engine-casing 25 through the medium of screws or bolts 29. From the cavity formed in the housing 27 steam is admitted to a steam-port 30, which leads into the main steam-chamber 12 of the engine. A second steam-inlet port or channel 31 is also formed in the side of the casing and is designed to conduct steam from the valve-housing at the side of the casing into the steam-chamber, as will be clearly seen in Fig. 3. The admission of the steam through 35 the ports or channels 30 and 31 is controlled through the medium of a revolving disk valve 32, keyed, as at 33, upon the main shaft 9, said valve being designed to turn with the shaft, and said disk valve is provided with 40 apertures or openings 34, designed to register at certain periods with the steam-inlet ports or channels, while the cut-away portions 34^a at the periphery of the disk register with the ports 30, so that the steam will be 45 admitted from the valve-housing into the main chamber of the engine to drive the pistons and disk wheel. The steam entering through the port 30 will follow the circular path formed between the disk wheel of the engine and the 50 interior wall of the casing and, striking against the projecting pistons, by impact and expansion will turn the disk wheel at a rapid rate of speed. The course of the steam entering through the port 30 is freely shown by the 55 path of the arrows in Fig. 3, and when the disk of the wheel has reached a certain point the steam driving the same will pass out through the exhaust-port 35, which port communicates with the steam-path in the casing.

60 As the projecting pistons pass the exhaust-port they strike against the adjacent abutting disk or block 22, and the recess or opening 23 therein permits the piston to pass over the abutment-block and continue its path of travel.

65 After passing the abutment-block to the left

in Fig. 3 the piston is subjected to the second impact charge of steam received from the inlet-port or steam-channel 31, which charge of steam continues the driving of the wheel, the charge from such latter port 31 passing 70 out through the exhaust-port 36, located adjacent to the right-hand abutment-disk in Fig. 3, the piston passing the abutment-disk to the right in a manner similar to that just described as to the left-hand abutment-disk, and 75 the operation of the engine is repeated. It is to be noted that the disk valve opens and closes the admission to the steam-inlet ports at certain predetermined times, so that while 80 a charge of steam from one inlet is being admitted to the engine the charge previously received from the opposite inlet will be exhausted.

It will be noted that the large gear-wheel 85 25, which is fast on the shaft 9 and meshes with the gear-wheels 24, will drive the shafts 21 21, upon which the abutment-disks are mounted, and causes the revolution of said disks to bring the recesses therein in the path of the passing pistons at the proper moment.

It will be noted that we have provided an exceedingly simple and compact engine and one which is capable of attaining a high degree of efficiency.

While we have shown and herein described one particular embodiment of our invention, it is of course to be understood that we do not limit ourselves to the precise details of construction shown herein, as there may be modifications and variations in certain respects without departing from the essential features of the invention or sacrificing any of the advantages thereof.

Having thus described our invention, we 105 claim as new and desire to secure by Letters Patent—

1. The combination of a casing, a shaft journaled therein, a disk mounted upon said shaft, a steam-path being formed between the periphery of the disk and the wall of the casing, a plurality of supplemental chambers communicating with the casing, shafts journaled in said casings, recessed abutment-blocks carried by said latter shafts, gearing interposed 110 between the shaft in the casing and the shafts in the chambers for imparting motion to the latter, a piston carried by the disk, a valve-housing secured to the side of the casing, a 115 plurality of communicating ports leading from the housing into the casing at different points, a self-seating disk valve rotating with the shaft of the casing and controlling the inlets, means for conducting steam into the valve-housing, and exhaust-ports leading from the 120 engine-casing, substantially as set forth.

2. The combination of a casing, a shaft journaled therein, a disk mounted within the casing upon said shaft, said disk having a plurality of spring-tensioned pistons, and also 130

having spring-packings arranged at the periphery thereof, means for admitting steam into the chamber of the casing to drive said disk by pressure against the pistons, a plurality of supplemental chambers communicating with the main chamber of the casing, recessed abutment-disks mounted upon shafts journaled in the supplemental chambers, a relatively large gear-wheel mounted upon the shaft at the exterior of the casing, relatively small gear-wheels carried by the shafts of the abutment-disks and rotated to bring the recessed portions thereof into position to per-

mit the passage of the pistons on the wheel-disk within the casing, and exhaust-ports for the escape of the operating charge from the engine, substantially as set forth.

In testimony whereof we have signed our names to this specification in the presence of two subscribing witnesses.

SEDGWICK MILLS WADE.
GEORGE EDWARD GARNER.
